LOOP CUTTING ATTACHMENT FOR
RIB-KNITTING MACHINES

John N. Gilbreath, Summerville, Ga.

Application December 5, 1949, Serial No. 131,204

5 Claims. (Cl. 66—147)

1

This invention relates to an improved automatic loop cutting attachment for circular rib-knitting machines, and has particular reference to improvements in the type of loop cutting attachment disclosed in my U. S. Patent No. 2,411,259, dated November 19, 1946.

While the attachment disclosed in my above mentioned patent is suitable for machines wherein rotation of the needle dial is prevented by means associated with the upper end of the dial post, it is not capable of use with machines in which rotation of the dial is prevented by dogs on the inside of the needle cylinder and the under side of the dial.

This is true because the dogs are so located as to interfere with positioning of the guard member and loop selecting needle of the attachment within the needle cylinder as shown in said patent.

The primary object of the present invention, therefore, is to provide an attachment of the above type which may be employed on any rib-knitting machine. I accomplish this object by extending the dial post to a point below the needle cylinder, and mounting the loop-engaging and cutting device on the lower portion of the dial post extension.

A further object is to provide an attachment of the above kind including a disk secured on the dial post extension and adapted to radially expand the tubular fabric as it is drawn downwardly from the needle cylinder, and a loop-engaging and cutting device carried by said fabric-expanding disk and arranged to automatically engage or select the similar end loops of the special removable courses which unite successive separable lengths of the tubular fabric, as said courses move downwardly from said disk.

A still further object is to provide an attachment of the above kind which is simple in construction and efficient in operation.

The exact nature of the present invention will become apparent from the following description when considered with the accompanying drawings, in which:

Figure 1 is a somewhat diagrammatic view, partly in vertical section and partly in elevation, showing a portion of a knitting machine equipped with a loop cutting attachment embodying the present invention.

Figure 2 is an enlarged view of the attachment, partly in vertical section and partly in elevation.

Figures 3 and 4 are horizontal sectional views taken respectively on the line 3—3 and on the line 4—4 of Figure 2.

2

Figure 5 is a bottom plan view of the attachment shown in Figure 2.

Referring in detail to the drawings, 5 indicates part of the fixed bed plate of a knitting machine, to which is secured a needle cylinder 6. Mounted for free rotation on the bed plate 5 is a bevel gear wheel 7, and mounted upon the wheel 7 is a cylinder cam ring 8 which is provided with the usual cams for imparting vertical reciprocating movement to the needles *a* of the needle cylinder. The needle dial 9, in which are guided the horizontal dial needles *b*, is secured on the lower end portion of a vertical post 10. The dial 9 is held against movement relative to the needle cylinder by dogs 11 and 12 respectively carried by the needle cylinder and the dial. Above the dial 9 is located the dial cam ring 13 which is provided on its under side with the usual cams for imparting horizontal reciprocating movement to the dial needles *b*, said dial cam ring being caused to rotate in unison with the cylinder cam ring by any suitable means.

In accordance with the present invention, the dial post is provided at its lower end with an extension 14 which projects below the needle cylinder and the bed plate, and which preferably consists of a shaft section having a reduced and threaded upper end portion or stem 15 screwed into a threaded socket provided in the lower end of the dial post. Secured on the extension 14 near the lower end thereof, as by means of a set screw 16 is a fabric-expanding disk 17 over and downwardly beyond which is drawn the ribbed tubular fabric *F* produced on the machine, and by means of which said fabric is expanded radially. Secured to the disk 17, as by means of a set screw 18, is an inclined guard pin 19 which projects downwardly and outwardly to a point slightly below and outwardly of the periphery of disk 17.

A substantially U-shaped loop-engaging or selecting needle or finger 20 is attached at one end to the disk 17 at one side of extension 14, as by means of a set screw 21, and this needle or finger extends downwardly from said disk under the lower end of said extension and has a free end 45 portion which extends upwardly at the opposite side of said extension to a point directly under and slightly spaced from lower free end of the guard pin 19. A loop-cutting blade 22 is fixed to the inside of the free end portion of needle or finger 20 adjacent the right portion of the latter, and this blade extends under the lower end of extension 14.

The fabric *F* consists of separable lengths or sections 23 united by special removable courses, as at 24, each section being knitted with a finish-

ing course at one end formed of selvage loops, and the removable or pull-out courses interengaging an end regular rib-loop course of one section and a selvage-loop course of the next section. Corresponding end loops of the respective special section-uniting courses are cut to free and thereby permit the latter to be pulled out or removed to separate the sections. As the knitted fabric passes the disk 17 in expanded condition, the regular rib-loop courses are held outwardly beyond the free end of the needle 20 by the guard pin 19, but the end loops of the special section-uniting courses pass inwardly between the adjacent ends of pin 19 and needle 20 so as to be engaged or selected by the latter. These engaged or selected loops pass downwardly on the needle or finger 20 until they engage and are severed by the blade 22, thereby freeing the section-uniting courses so that they may be removed or pulled out to separate the fabric sections. As is well known, the fabric sections are employed as hose tops, cuffs, or the like.

In practice, the present attachment has proven highly efficient for the intended purpose, and it may be readily and cheaply manufactured, as well as readily applied to all types of circular rib-knitting machines. Modifications and changes in details of construction are contemplated within the spirit of the invention as claimed.

What is claimed as new is:

1. In a knitting machine having mechanism for producing a succession of tubular fabric sections united by special removable courses and including a needle cylinder, and a dial post having an extension depending below the needle cylinder, loop-engaging and severing means including a fabric-expanding disk secured on the dial post extension, a depending guard pin carried by and extending outwardly beyond the periphery of said disk, a depending finger fixed at one end to said disk and having an upwardly extending end portion terminating under the lower end of said guard pin for receiving corresponding end loops of the removable courses, and a blade fixed to the inner side of said upwardly extending end portion of the finger for severing said end loops so as to permit removal of said removable courses for separation of the fabric sections.

2. In a knitting machine having mechanism for producing a succession of tubular fabric sections united by special removable courses and including a needle cylinder, and a dial post, a loop-cutting attachment including an extension attached to the lower end of said dial post and depending below the needle cylinder, a loop-selecting finger mounted on the lower portion of said extension and having an upwardly extend-

ing end portion for receiving corresponding end loops of the removable courses, a guard member mounted on said extension and having a lower end disposed over the free end of said upwardly extending end portion of the finger, and a blade fixed to said upwardly extending end portion of the finger for severing said end loops.

3. In a knitting machine having mechanism for producing a succession of tubular fabric sections united by special removable courses and including a needle cylinder, and a dial post having an extension depending below the needle cylinder, loop-engaging and severing means including a fabric-expanding disk secured on the dial post extension, a depending guard pin carried by and extending outwardly beyond the periphery of said disk, a depending substantially U-shaped finger fixed at one end to said disk and having an upwardly extending end portion terminating under the lower end of said guard pin for receiving corresponding end loops of the removable courses, and a blade fixed to the inner side of said upwardly extending end portion of the finger for severing said end loops so as to permit removal of said removable courses for separation of the fabric sections, said blade extending under the lower end of the dial post extension.

4. In a knitting machine having mechanism for producing a succession of tubular fabric sections united by removable courses having corresponding end loops, and including a dial post, a loop cutting attachment including an extension attached to the lower end of said dial post, an end loop selecting finger and a guard for said finger mounted on said extension, and a loop severing blade fixed to said finger.

5. In a knitting machine having mechanism for producing a succession of tubular fabric sections united by removable courses having corresponding end loops, and including a dial post, a loop cutting attachment including an extension attached to the lower end of said dial post, an end loop selecting finger and a guard for said finger, a loop severing blade fixed to said finger, and a fabric expanding disk secured on said extension and comprising the mounting for said finger and said guard.
